UNITED STATES PATENT OFFICE.

IVAN L. OSTERHOUT, OF COLFAX, WASHINGTON.

ADJUSTABLE READING-RACK.

1,398,601.

Specification of Letters Patent. Patented Nov. 29, 1921.

Application filed May 28, 1920. Serial No. 385,019.

To all whom it may concern:

Be it known that I, IVAN L. OSTERHOUT, a citizen of the United States, residing at Colfax, in the county of Whitman and State 5 of Washington, have invented a new and useful Adjustable Reading-Rack, of which the following is a specification.

The object of my invention is to provide an improved illuminated reading rack 10 specially adapted for enabling a person to read while in bed and having a novel combination of means for adjusting the rack in all directions and securing it in adjusted position at various points, including means 15 for holding either small or large volumes, as disclosed in the accompanying drawings, in which—

Figure 1 is a perspective view of the rack in use;

20 Fig. 2 is a side elevation of the invention;

Fig. 3 is a detail sectional view on the line 3—3 of Fig. 2;

Fig. 4 is a front plan of the rack or book rest; and

25 Fig. 5 is a modified form of the invention having the lamp cord suspended from the successive sections of the lazy tongs by rings R.

Like letters designate like parts in each 30 of the views.

Referring to the accompanying drawings I provide a suitable bracket P adapted to engage any suitable article of furniture, such as the side rail of a bed, and having a 35 suitable thumb-screw A for releasably securing the bracket to the article of furniture; and a suitable tube B mounted on and affixed to the bracket. Tube B is provided with a suitable opening Q near its lower

40 end, through which the electric lamp cord L passes. I provide a suitable rack supporting tubular arm D mounted in tube B and vertically adjustable therein; and a suitable thumb-screw C mounted in tube B

45 and adapted to engage tubular arm D to secure the same in adjusted position. Arm D is adjustable both vertically and radially. Mounted on the end of tubular arm D, I provide a support or hinge E for the lazy

50 tongs F, one of the series of consecutively connected arms of the lazy tongs being of tubular construction, and through which the electric lamp cord D is threaded as shown in Fig. 2. I may, however, provide 55 lazy tongs of solid construction having rings R mounted on successive sections and

through which the lamp cord L is threaded exterior to the lazy tongs. I provide a suitable rack support or hinge H attached to the free end of the lazy tongs, and carrying a rack and lamp supporting hinge G on which is mounted the rack or book rest K, which is supported adjustably by member H which engages the slot H' at the desired angle by means of a suitable adjusting screw I. Also mounted on hinge G I provide a tubular lamp supporting arm J carrying the electric lamp N. Reading rack K is provided with a suitable base O and with suitable spring clips or fasteners 70 M, which are laterally adjustable on the rack K to make it possible to hold a small book or magazine equally as well as a larger volume.

The device is especially designed for the 75 use of patients who are confined to a bed, and is provided with a series of means which permit the device to be readily adjusted vertically, laterally, and radially, and which in addition permit of independent adjustment of the rack relative to the lamp, and of adjustment of the main supporting structure or lazy tongs relative to the main telescopic supporting tubes. I provide the 80 novel tubular lazy tong members as shown, 85 permitting of the convenient mounting and concealment of the lamp cord, while not interfering with the adjustment of the structure in a variety of directions.

The operation of the various means for 90 adjustment is disclosed in the accompanying drawings, and is described above in connection with the explanation of the structure.

What I claim is:

1. In an adjustable reading rack, the combination of a bracket releasably attached to an article of furniture, a tube mounted on the bracket, a second L-shaped tube telescopically mounted and radially swingable 100 in the first named tube, said tubes having channels of suitable size for the threading of an electric light cord therethrough, means for securing the second tube in adjusted positions, longitudinally extensible means attached to the second tube for supporting a book rack, said means including means for extensibly supporting an electric light cord, a book rack, and means adjustably connecting the book rack to the aforesaid 105 extensible means to permit of vertical and tiltable adjustment.

2. In an adjustable reading rack, the combination of a supporting bracket releasably attachable to an article of furniture, telescoping tubes mounted on said bracket, said tubes having channels of suitable size for an electric lighting cord to be threaded therethrough, extensible means attached to the uppermost of said tubes, said extensible means including means through which an electric lighting cord may be threaded to prevent its hanging loose, a reading rack supporting member adjustably mounted on the extensible means and vertically adjustable relative thereto, and a reading rack tiltably mounted on the last said means, substantially as shown.
3. In an adjustable illuminated reading rack, the combination of a supporting member adapted to be suitably secured to an article of furniture, a tube mounted on said supporting member and having an opening in its lower end to receive an electric light cord, a second tubular member telescopically mounted in the first tubular member and having a channel for the electric light cord and an opening for the passage of the cord near the end of the tube, means for adjusting the position of the inner relative to the outer tube, a lazy tongs element mounted on the inner tube, means in connection with the lazy tongs element for threading the electric light cord along and through same,

means on the end of the lazy tongs element for supporting a reading rack, said means being vertically adjustable, a reading rack, a tube affixed to the means for supporting the reading rack, through which the electric lighting cord may be threaded, said means terminating in a suitable position above the reading rack for receiving an electric lamp, substantially as shown and for the purposes described.

4. In an adjustable illuminatable reading rack, the combination of means for attaching the rack to a suitable article of furniture, a telescopic supporting device, means for securing said telescopic device in vertically and radially adjusted positions, said telescopic device being adapted to contain an electric lighting cord in concealed position, an extensible lazy tongs element attached to said lazy tongs element, means for threading an electric cable along and through the lazy tongs element, a reading rack supporting member on the lazy tongs element, a reading rack tiltably mounted on said member, a hollow electric lighting cord containing element affixed to the reading rack supporting member and terminating in a position above the reading rack and adapted to carry an electric lamp to illuminate the rack, substantially as shown.

IVAN L. OSTERHOUT.
